UNITED STATES PATENT OFFICE

JOSEPH E. FORSYTH, OF CHICAGO, ILLINOIS, ASSIGNOR TO FORSYTH DRAFT-GEAR CORPORATION, A CORPORATION OF ILLINOIS

DRAFT GEAR

Application filed December 6, 1926. Serial No. 152,838.

This invention relates particularly to draft-gears for use in connection with railway cars.

The primary object is to provide an improved draft-gear of high capacity and which is of improved operation and capable of withstanding enormous strain.

The invention is illustrated in its preferred embodiment in the accompanying drawings, in which—

Fig. 1 is a broken plan sectional view showing details of the improved draft-gear; Fig. 2, a broken transverse vertical sectional view taken as indicated at line 2—2 of Fig. 1; Fig. 3, a perspective view of a spring-cap employed; and Fig. 4, a perspective view of a hollow follower-block employed.

In the preferred embodiment illustrated, A designates the substructure of a car, the intermediate longitudinal beams being designated A' and A²; B, B', the front and rear stops, respectively, for the draft-gear, these stops being rigidly secured by the beams A' and A²; C, a yoke which embraces the follower-blocks of the draft-gear and which is connected with a draw-bar C' of the car in the usual manner; D, D', the front and rear follower-blocks, respectively; E, E', the front and rear sets of springs, respectively; F, F', the front and rear spring-caps, respectively; and G, G', a pair of complementary lever-sections, which, together, constitute a compensating lever interposed between the spring-caps and the opposed shoulders of the follower-blocks.

The substructure of the car may be of standard construction, the improved draft-gear being adapted to be mounted therein, being housed between the longitudinal beams A' and A². These beams are shown connected at their bottom portions by cross-members 1 upon which the yoke C is slidably supported. A cross-member 2 is disposed above the yoke.

The follower-blocks D and D' are of the same construction, but reversed in position. These blocks are provided with chambers 3 to accommodate the springs and spring-caps. Each block preferably is cast to provide a top wall 4, a bottom wall 5, a plane lateral wall 6, a part-cylindrical wall, or web, 7,

opposed to the wall 6, and an end wall 8, the end walls 8 being embraced by the end portion of the yoke C.

At their inner or adjacent ends, the follower-blocks are provided with end walls 9 which afford stops, or shoulders, which limit the closing action of the draft-gear. The end walls 9 are cut away so as to leave the chambers 3 open at one end. Each end wall 9 is provided with a toothed sector 9^a. Each of the follower-blocks has a lateral extension formed by extending the top and bottom walls 4 and 5 and the end walls 8 and 9, the respective extensions being designated 4^a, 5^a, 8^a and 9^a. The convex portion of the web 7 is backed by intermediate strengthening ribs 7^a. The wall extensions described terminate in a plane 10 which is adapted to serve as a bearing surface when the block is interposed between the frame-members A' and A², the outer surface of the wall 6 serving as a similar bearing surface.

Each spring-cap is of the form shown in Fig. 3. Thus, each cap F, for example, is provided with a head 11 having a concave end surface 11^a which is provided with horizontal corrugations. Also, the spring-cap is provided at one side with a concavo-convex wall 12 and at the opposite side with a plane wall 13. The walls 12 and 13 constitute the shank of the spring-cap and afford between them a chamber 14 adapted to receive one end of a set of springs. It will be noted from Figs. 2 and 3 that the wall 13 is equipped at its inner side with fillets 13^a which serve to brace the wall 13. The fillets taper, as shown in Fig. 3, and have curved inner surfaces which conform to the spring, as illustrated in Fig. 2.

The lever which is interposed between the follower-blocks and opposed spring-caps preferably is composed of the two members G and G', which are capable of moving, or sliding, with relation to each other. This two-member lever acts as a single lever, but is self-adjusting in length, the general purpose being to allow a compensating movement of the members in order that they may adjust themselves properly at all times with 100

respect to their bearings during the pulling and buffing operations.

Each lever member has a head portion which provides a convexity 15 having corrugations 15^a which register with the corrugations of the concavity 11^a of the spring-cap. Also, the lever-member presents opposite the convexity 15 a rack-portion 16 having teeth which register with the teeth of the sector 9^a of the opposed follower-block; and each lever-member is further provided with a shank-portion 17. The toothed portions of the lever-members engage the toothed portions of the follower-blocks in the manner illustrated in Fig. 1. The lever-members are adapted to have limited sliding action upon each other, and preferably are provided with stud and slot connections 18 which are chiefly useful in facilitating the assembly of the device. There is sufficient play allowed to permit the relative sliding action of the lever-members necessary for the self-adjustment which occurs during the rocking action of the lever. If desired, an integral lever may be employed, although the two-member lever is much preferred.

It is desirable, in practice, to place the springs under initial compression and, for convenience in assembling the draft-gear, rods 19 are employed for this purpose. These rods extend through suitable perforations, or recesses, with which the various members are provided and serve to connect the follower-blocks, as illustrated in Fig. 1. The rods are capable of sliding through the perforations, so that the actions of closing and opening the draft-gear in operation are not interfered with.

In the operation of the device, when the yoke C is drawn forwardly, it causes the follower-block D' to move forwardly away from the stops B'. During this action, the two-member lever undergoes a rocking movement, and heavy friction is exerted in the draft-gear, especially at the corrugated concavo-convex bearing surfaces between the lever-members and the spring-caps. The springs resist the collapsing action of the draft-gear and later restore the draft-gear to the extended position. Under buffing action, a similar result is obtained, but in this case the follower-block D' remains against the stops B' while the follower-block D moves away from the stops B.

It may be added that in the operation of the gear, the heavy friction exerted between the corrugations of the lever and of the spring-caps tend to rotate the spring-caps in a counter-clockwise direction, as viewed in Fig. 1. This tendency is counteracted especially by reaction forces between the part-cylindrical webs 7 and the remote end portions of the shank-walls 12, and also by reactive forces between the inner end portions 65 of the walls 13 of the spring-caps and the

adjacent portions of the walls 6 of the follower-blocks. Thus, it will be understood that the lateral walls 6 and 7 of the follower-blocks are subjected to heavy strains and frictional forces. The spring-caps will nevertheless, adjust themselves to compensate for wear.

The follower-blocks are staunchly constructed and well adapted to overcome the turning moments exerted upon the spring-caps during the use of the draft-gear.

It will be understood from Figs. 1 and 2 that the spring-caps F and F' partially overlap each other crosswise of the draft-gear. The same is true with respect to the chambers 3 of the follower-blocks, thus enabling springs of relatively large diameter to be employed in a construction having a rocking-lever interposed between the spring-caps and the follower-blocks in which the spring-caps are housed. It has been demonstrated that the improved device is capable of withstanding buffing and pulling stresses of enormous magnitude.

The present invention constitutes an improved modification of the invention disclosed in my U. S. Patent No. 1,679,301.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. In a draft-gear, the combination of a pair of opposed follower-blocks, each presenting an inner end-bearing abutment and each having a chamber provided with opposed lateral walls, spring-caps mounted in said chambers having shank-portions confined between said lateral walls, a spring confined between said spring-caps and the remote ends of said chambers, and a rock-lever having head-portions confined between said spring-caps and the opposed bearing abutments of the follower-blocks.

2. In a draft-gear, a pair of opposed follower-blocks provided with chambers having at one side part-cylindrical lateral walls and at the other side plane lateral walls, spring-caps mounted in said chambers having hollow shank-portions provided with lateral walls engaging the lateral walls of said chambers, springs housed in said chambers and extending into the hollow shanks of said spring-caps, and a rock-lever having head-portions confined between said spring-caps and end-abutments with which said follower-blocks are equipped.

3. In a draft-gear, a pair of opposed follower-blocks having longitudinal chambers which are out of alignment with each other, said chambers having walls on all sides and at the remote ends of the blocks, said cham-

- bers being open at adjacent ends, spring-caps mounted in said chambers and provided with hollow shanks engaging opposed lateral walls of said chambers, springs confined in said chambers and extending into said hollow shanks, said spring-caps being provided at adjacent sides with concavities and horizontal corrugations at said concavities, and a rock-lever having head-portions presenting corrugated convexities received by said corrugated concavities, and toothed connections between the head-portions of said lever and the inner end-abutments of said follower-blocks.
4. In a draft-gear, a follower-block having therein a chamber open at one end and otherwise provided with closed walls, said follower-block having a lateral extension at one side of said chamber equipped with a toothed end-abutment.
5. In combination in a draft-gear, a pair of opposed follower-blocks having chambers out of alignment with each other and open at adjacent ends, each of said chambers being provided with opposed lateral walls, spring-caps in said chambers provided with hollow shanks having lateral walls engaging the lateral walls of said chambers, springs confined within said chambers and extending into said hollow shanks, said spring-caps being provided with horizontally corrugated concavities, and a two-member lever confined between said spring-caps and end-abutments with which said follower-blocks are provided, said lever-members being provided with corrugated convexities engaging said corrugated concavities and being provided with toothed portions engaging teeth with which said abutments are equipped, said members of said lever being relatively shiftable to permit self-adjustment.

JOSEPH E. FORSYTH.
